FIG. 11.

FIG. 12.

FIGURE 1 is an isometric view of a rubber stamp or the like showing my new design, the broken line showing in this view of wall rod being merely illustrative of the manner of securing the stamp to a wall;

FIGURE 2 is a right end elevational view of the rubber stamp or the like shown in FIGURE 1;

FIGURE 3 is a front elevational view thereof;

FIGURE 4 is a rear elevational view thereof;

FIGURE 5 is a top plan view thereof;

FIGURE 6 is a bottom plan view thereof;

FIGURE 7 is an isometric view of another embodiment of the rubber stamp or the like shown in FIGURE 1 adapted to receive a smaller stamp face and wherein the indented hanger slot has been rounded, the broken line showing in this view of a wall rod being merely illustrative of the manner of securing the stamp to a wall;

FIGURE 8 is a right end elevational view of the rubber stamp or the like shown in FIGURE 7;

FIGURE 9 is a front elevational view thereof;

FIGURE 10 is a rear elevational view thereof;

FIGURE 11 is a top plan view thereof; and FIGURE 12 is a bottom plan view thereof.

The essential features of the design reside in the portions shown in solid lines.

I claim:

The ornamental design for a rubber stamp or the like, substantially as shown and described.
